UNITED STATES PATENT OFFICE.

JOHANNES PAUL BECKER, OF BERKELEY, CALIFORNIA.

DESIGN FOR AN AUTOMOBILE SIGNAL-LIGHT.

50,930.

Specification for Design.

Patented June 19, 1917.

Application filed April 25, 1917. Serial No. 164,552. Term of patent 3½ years.

To all whom it may concern:

Be it known that I, JOHANNES P. BECKER, a citizen of the United States, residing at Berkeley, in the county of Alameda and State of California, have invented a new, original, and ornamental Design for an Automobile Signal-Light, of which the following is a specification, reference being had to the accompanying drawings, forming part thereof.

Figure 1 is a perspective view of the automobile signal light.

Fig. 2 is a front view of the same.

I claim:

The ornamental design for an automobile signal light, as shown.

JOHANNES PAUL BECKER.
